(57) **CLAIM**

The ornamental design for a textured split-shot fishing weight, as shown and described.

DESCRIPTION

FIG. 1 is a top plan view of a textured split-shot fishing weight showing my new design;

FIG. 2 is a bottom plan view thereof;

FIG. 3 is a left side elevation view thereof;

FIG. 4 is a right side elevation view thereof;

FIG. 5 is a front elevation view thereof

FIG. 6 is a rear elevation view thereof; and,

FIG. 7 is a perspective view thereof.

The broken lines in all figures depict environmental subject matter only and form no part of the claimed design.
